(57) **CLAIM**

The ornamental design for a one-piece word-symbol tag for product panels, as shown and described.

DESCRIPTION

FIG. 1 is a perspective view of a one-piece word-symbol tag for product panels in accordance with the present invention; FIG. 2 is a front view thereof;

FIG. 3 is a right side view thereof showing a broken line rear side;

FIG. 4 is a left side view thereof showing a broken line rear side;

FIG. 5 is a top plan view thereof showing a broken line rear side; and,

FIG. 6 is a bottom plan view thereof showing a broken line rear side.

The broken lines shown are for illustrative purposes only and form no part of the claimed design.
